UNITED STATES PATENT OFFICE.

FRIEDRICH C. FISCHER, OF PHILADELPHIA, PENNSYLVANIA.

COMMUTATOR.

984,655.

Specification of Letters Patent. Patented Feb. 21, 1911.

Application filed September 8, 1910. Serial No. 581,040.

To all whom it may concern:

Be it known that I, FRIEDRICH C. FISCHER, a subject of the Emperor of Germany, but who have declared my intention of becoming a citizen of the United States, and now residing at the city of Philadelphia, in the county of Philadelphia and State of Pennsylvania, have invented certain new and useful Improvements in Commutators, of which the following is a specification.

A commutator is generally arranged with copper bars and mica sections disposed longitudinally side by side about the axis of the same. The mica commonly used being termed "micanite", which consists of small pieces of mica held together by shellac or varnish. In service, as often happens bits of copper, carbon or particles of oil will deposit on the micanite as well as in small cracks or crevices formed in the same, thus furnishing a good conducting path to the copper bars of the commutator and hence for the current to leak from one copper bar to the other thereof, resulting finally in what is called "pitting". The almost universal practice, in order to provide for pitting is to scrape out the formed cracks or crevices and fill with French chalk, powdered mica, silicate of soda or the like but this has been very unsatisfactory, because soon leakage again begins beneath the portion of the commutator packed with such material.

The principal object of my invention is to in case of "pitting" provide a simple, practical, effective and inexpensive manner of providing for "pitting".

The nature and scope of my present invention will be more fully understood from the following description taken in connection with the accompanying drawings forming part hereof, in which

Figure 1, is a perspective view of the sections of a commutator, showing the alternately arranged metal and "micanite" sections or parts thereof, and also illustrative of the irregular "pitting" of the micanite sections of the same taking place in the service thereof. Fig. 2, is a transverse sectional view through a commutator, showing the assembled copper and mica or "micanite" sections or parts of the commutator and in end elevation an instrument of a preferred arrangement for forming required shaped recesses in defective parts or sections of the commutator to receive such repair inserts.

Figs. 3 and 4, are perspective views respectively, of sections of a commutator with their variable shaped recesses to receive corresponding repair inserts of mica or micanite; and Figs. 5, 6 and 7, are respectively, in elevation several different forms of recesses that are provided to receive repair insert parts, so as to quickly remedy "pitting" of the insulating sections or parts of a commutator.

In the drawings, A represents a commutator composed of two series of oblong sections or parts a^1 and a^2 , of copper and mica, micanite or other similar insulating material, in operative relation arranged side by side, throughout the structure as shown in Fig. 2.

b and b^1 , are two circular saws of differing diameters and each provided with teeth around the peripheries of the same. The radius of the largest of the saws clamped together is about half an inch less than the radial depth of the insulation of the micanite or other material separating the copper commutator bars. In this way the repair operation can be effected without danger of cutting entirely through the commutator. The saws as shown, are mounted on a shaft b^2 , with which operating means, not shown, may be connected for revolving the same. The clamped saws to operate are lowered onto the defective section and rotated and shifted during cutting into the mica or micanite deep enough to entirely remove defective material so that the repair part or piece to be inserted will correspond substantially to the recess made by the saws. When the repair insert or part has been inserted into the recess it is cemented therein. If after insertion it is found pitting has extended to a greater extent of the mica or micanite part or section of the commutator than was supposed, the clamped saws can be readily shifted to effect a cut substantially coextensive with that of the impaired structure to receive a repair insert or part, according to my invention and so as also to be readily secured in place therein.

Having thus described the nature and objects of my invention, what I claim as new and desire to secure by Letters Patent is:—

The herein described mode of repairing commutators, which consists in mechanically forming an incision of variable shape or form in a defective part or section of a

commutator at one time and applying an insert part or section in shape or form corresponding to that of the incision and securing in position, to again establish electrically normal relations or conditions of the commutator.

In witness whereof, I have hereunto set

my signature in the presence of two subscribing witnesses.

FRIEDRICH C. FISCHER.
